UNITED STATES PATENT OFFICE.

FRANK B. GRIFFIN, OF OSHKOSH, WISCONSIN, ASSIGNOR TO FRANK S. FELL AND WILLIAM R. HILL, BOTH OF OSHKOSH, WISCONSIN.

CONTACT-BREAKER FOR INDUCTION-COILS.

No. 857,458.

Specification of Letters Patent.

Patented June 18, 1907.

Application filed December 3, 1906. Serial No. 346,161.

To all whom it may concern:

Be it known that I, FRANK B. GRIFFIN, a citizen of the United States, residing at Oshkosh, in the county of Winnebago and State of Wisconsin, have invented certain new and useful Improvements in Contact-Breakers for Induction-Coils, of which the following is a specification.

My invention relates to contact-breakers for induction-coils.

The objects of my invention are to provide a positive action of the spring, a thorough break and an adjusted bearing relative to the spring power.

An important feature of my invention is an adjustable stud or lug that is to be properly adjusted at the manufactory relative to the spring tension and then rendered non-adjustable so that in ordinary usage the operator cannot disarrange the adjustment. After the vibrator is tested and adjusted at the manufactory, future adjustment can only properly be made by the ordinary thumb-screw adjustment.

In the accompanying drawing Figure 1 represents a plan view and Fig. 2 a vertical section of my invention. Fig. 3 illustrates a plan view of the spring-base.

Referring to the drawings by numerals, 2 represents the coil casing, 3 the spring-base attached thereto, as by ordinary screws 4, 4.

5 represents the primary spring and 6 a downwardly curved secondary spring both seated in the depression 7 in the spring-base or head 3 and preferably secured by the set-screw 8 passing through ordinary eyes in both springs and into the threaded opening 9.

10 represents an extension to the spring-base for the purpose of carrying the stud 11. I regard the stud 11 as an important feature of my invention. It will be observed that it is threaded at the base and may be passed through a corresponding threaded opening in the extension 10 and, in its pressure against

the springs 5 and 6, thoroughly and exactly adjusted with reference to the tension of the springs. This is properly done at the manufactory and after proper adjustment the lower portion of the stud is preferably cut away in line with the line of the base or the casing so as to effectually prevent further manipulation of this adjustment, by an ignorant operator. In the use of vibrators heretofore where double adjustments have been provided, the efficiency of the vibrator has

been destroyed by losing the primary adjustment and then failing to regain a relative adjustment between the two adjustments.

In my invention, the ordinary secondary adjustment is used comprising the bridge 12, and the thumb-screw adjustment 13 carrying one of the platinum points 14, the opposite platinum point 15 being located upon the spring 6.

I provide a thin armature 16 with a minimum weight. By means of the secondary downwardly curved spring 6 and the delicate adjustment of the stud 11, I afford an absolute break without a tremble and thus assure a long unbroken spark from the spark-plug. The double spring serves to balance the vibration.

What I claim is:—

1. A device of the character described, comprising a base plate, a magnet mounted adjacent thereto, an armature for said magnet, a spring for said armature, said spring being secured to said base, means on said base for regulating the tension of said spring, and means positioned adjacent to said magnet for assisting said tensioning means and holding said spring in a predetermined position.

2. A device of the character described, comprising a casing and a magnet mounted therein, a contact breaker for said magnet comprising a plurality of springs and means for varying the tension of said spring.

3. A circuit breaker, comprising a base, a straight flat spring, means for adjusting the vibration of said spring, and means for damping the movement of said spring.

4. A circuit breaker comprising a base, a vibrating spring secured thereto, means near one end thereof for regulating the angle of said spring when out of operation, and adjusting means at the opposite end of said spring for regulating the length of the movement of said spring.

5. A circuit breaker comprising a base, a vibrator mounted thereon, a bowed spring in contact with said vibrator for preventing trembling of the same and means for regulating the tension of said spring.

6. A circuit breaker comprising a base and vibrator, a plurality of means for regulating the tension of said vibrator, and means for damping the tremble of said vibrator.

7. A circuit breaker comprising a base, a vibrator secured thereto, adjustable means

for normally holding said vibrator in an elevated position, a bowed spring for preventing trembling during the movement of said vibrator and a set screw for regulating the 5 tension of said spring.

8. A circuit breaker comprising a base, a vibrator secured thereto, adjustable means for varying the length of vibration of said vibrator, adjustable means for regulating the 10 tension of said vibrator, and means for per-

mitting the vibrator to operate with but one vibration for each rupture of the circuit.

In testimony whereof I have signed my name to this specification in the presence of two subscribing witnesses.

FRANK B. GRIFFIN.
